Des. 202,540

Patented Oct. 19, 1965

202,540

ROOFER'S HIP PAD

William H. Nicholas, Los Angeles, and Robert G. Nicholas, Sierra Madre, Calif., assignors to McGuire-Nicholas Mfg. Co., Los Angeles, Calif., a corporation of California

Filed May 7, 1964, Ser. No. 79,876

Term of patent 14 years

(Cl. D3—26)

FIGURE 1 is a top plan view of our novel design for roofer's hip pad.

FIGURE 2 is a side view thereof, as seen from the right-hand side of FIGURE 1.

FIGURE 3 is a bottom plan view thereof.

We claim:

The ornamental design for roofer's hip pad substantially as shown.
